UNITED STATES PATENT OFFICE

EDWIN G. FRANCK, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed May 25, 1931. Serial No. 539,943.

The invention relates to removable car roofs, more particularly designed for use in connection with gondola freight cars to adapt the same for the carrying of a load which must be protected from the weather. It is the object of the invention

First, to obtain a construction which can be quickly and easily applied or removed from the car;

Second, to facilitate the easy loading of the car without necessity of removing the entire roof;

Third, to obtain various advantages as hereinafter set forth.

15 In the drawings:

Figure 1 is a plan view;

Figure 2 is an enlarged side elevation of a portion of the roof as applied to the car;

Figure 3 is a plan view thereof;

20 Figure 4 is a cross section on line 4—4 of Figure 1;

Figure 5 is an end elevation;

Figure 6 is a cross section on line 6—6 of Figure 1;

25 Figure 7 is a longitudinal section showing the joint between adjacent hinge sections;

Figure 8 is a section on line 8—8 of Figure 1;

Figure 9 is a section on line 9—9 of Figure 1.

Railway freight cars of the type known as gondola are usually constructed with metal sides surrounding the platform and reinforced at their upper edges by angle bars.

30 These angle bars are usually arranged to have their horizontal flanges extend outward from the sides and ends of the car and reinforced at their outer edges by a bulb or heavy bead. With my improved construction of

40 detachable roof I utilize these angle bars as a support and the bead at the edge thereof as a means for clamping or holding down the roof upon the car body. In detail, the roof comprises a plurality of sections separately engageable with or removable from the car body and as shown in Figure 1, there are two of such sections arranged upon the opposite sides of the longitudinal center of the car. Each section is formed of a series of

45 carlines A preferably of inverted channel

cross section with outwardly extended base flanges and a series of roofing sheets B having overlapping edges riveted to each other and to a supporting carline. The carlines are bent to give a slight slant or pitch to the roof on opposite sides of the ridge and the roofing plates terminate short of the ridge so as to leave a central opening for loading the car. Each sheet has an upturned flange B' at its inner end and at its outer or eaves end a downturned flange B² which overlaps the beaded edge of the angle C of the car body. Longitudinally extending angle bars D reinforce the downturned flanges B² and the inwardly extending flanges of these angle bars rest upon the angles C to support the roof. The angle bars D are riveted or otherwise attached to the carlines A.

55 The space between the inner ends of the sheets B is closed by a series of hinged covers E which when the car is being loaded or unloaded may be swung to one side so as to clear the opening between the sheets. This construction is shown in Figure 6 in which F are cap shaped sheets extending longitudinally of the car having downturned edges F' and outwardly extending flanges F² which rest upon the sheets B. At one side this cap member is attached to the sheet by a hinge fitting G so located as to permit the cap to swing clear. At the opposite side is a clamping fitting H for engaging the flange F² and holding the same down upon the sheet B. The caps F are provided with saddles I which in turn support running board sections J, 60 the ends of which are in proximity to the ends of the similar sections on an adjacent hinged cover.

65 Between the separately removable sections of the roof there is provided removable weatherproofing means as illustrated in Figure 8. This consists of transversely extending caps K which embrace upstanding end flanges L on the adjacent sections, these flanges being reinforced by angle bars M. The caps are secured down by fastening devices N which as illustrated are headed pins passing through the angles M and flanges of the caps K and secured by removable cotter pins or other locking means. The transverse 70

caps K extend the length of the sheets B and the space between the ends thereof is weatherproofed by a junction cap O. At opposite ends of the car and on opposite sides thereof are transverse running boards P, preferably a series of spaced boards, which are secured upon supporting angle bars Q with depending end portions Q' attached to the angle bars D.

With the construction as thus far described, the roof sections may be placed upon the car adjacent to each other and to facilitate this lifting brackets R are placed at intervals to provide an easy engagement with the hook of a hoist. When the sections are in position they are clamped down at the eaves and I preferably provide a quick clamping means of the following construction:

S are hinge brackets riveted to the downturned flanges B² and extending beneath the same. T are angle bent arms pivoted at their lower ends to the bracket S and adapted to extend upward inside of the flange B² and angle D and to bear against the under side of the bulb or bead on the angle bar C. Clamping bolts U engage the arms T and pass outward through apertures in the angle D and flanges B². Nuts N' on these bolts are adapted to be tightened thereby clamping the arms T against the under side of the bulb.

In loading the car any one or more of the hinge sections E may be opened by swinging the same back on the hinge G which will provide a sufficient opening to receive the load.

After loading these hinge sections are swung back and are locked by the clamping members H.

What I claim as my invention is:

1. The combination with an open car of the gondola type having outwardly extending reinforcing flanges at the top of its sides, of a temporary roof therefor comprising a plurality of sections arranged end to end and together covering the car, said sections having downturned flanges at the eaves and at the ends of the car, weatherproofing means between adjacent sections and clamping means secured to the downturned eaves flanges hooking under and engageable with the under side 50 of the flanged edges of the car.

2. A roof for open cars of the gondola type comprising a plurality of sections arranged end to end and together covering the car, each of said sections extending from eaves to eaves and having downturned weatherproofing flanges at the eaves and means mounted on said downturned flanges for hooking under and clamping said section to the flanged upper end of the car.

3. A roof for open cars of the gondola type comprising a roof section extending from eaves to eaves with downturned flanges at the eaves, means for securing said downturned flanges to the car and a hinged cover 65 for opening in the ridge portion of said roof

section providing access for loading and unloading.

4. A roof for open cars of the gondola type comprising a roof section extending from eaves to eaves, said section having roofing sheets spaced from each other on opposite sides of the ridge to provide an opening and extending to the eaves with downturned flanges at the eaves, and a cap for removably covering the opening between said spaced sheets providing access for loading and unloading.

5. A roof for open cars of the gondola type comprising a plurality of sections arranged end to end and together covering the car, each of said sections extending from eaves to eaves and having downturned weatherproofing flanges at the eaves and means carried by said downturned flanges and operable externally of the car for hooking under and clamping against the under side of the flanged upper end of the car.

In testimony whereof I affix my signature.

EDWIN G. FRANCK.
